GAS LIGHT

Donald E. Dailey, Evansville, Ind., assignor to Arkla
Industries Inc., Evansville, Ind., a corporation of
Delaware

Filed July 24, 1964, Ser. No. 81,000

Term of patent 14 years

(Cl. D48—31)

Fig. 1.

Fig. 3.

Fig. 4.

Fig. 2.

Fig. 6.

Fig. 5.

FIGURE 1 is a perspective view of a gas light showing my new design;

FIGURE 2 is a side elevation view of the gas light;

FIGURE 3 is a top plan view of the gas light;

FIGURE 4 is a bottom plan view of the gas light;

FIGURE 5 is a perspective view of the gas light in the open position thereof;

FIGURE 6 is a perspective view of the gas light with the roof thereof removed for the purpose of better illustrating the body portion of the gas light.

The dotted line showing is for illustrative purposes only.

I claim:

The ornamental design for a gas light, substantially as shown and described.
